UNITED STATES PATENT OFFICE.

JOHN F. O'CONNOR, OF CHICAGO, ILLINOIS, ASSIGNOR TO WILLIAM H. MINER, OF CHAZY, NEW YORK.

DRAW-BAR AND YOKE CONNECTION

1,179,747.

Specification of Letters Patent. Patented Apr. 18, 1916.

Application filed March 18, 1915. Serial No. 15,348.

To all whom it may concern:

Be it known that I, JOHN F. O'CONNOR, a citizen of the United States, residing at Chicago, in the county of Cook and State of Illinois, have invented a certain new and useful Improvement in Draw-Bar and Yoke Connections, of which the following is a full, clear, concise, and exact description, reference being had to the accompanying drawings, forming a part of this specification.

This invention relates to improvements in draw-bar and yoke connections.

An object of the invention is to provide simple, readily attachable and detachable means for connecting a yoke and draw-bar for railway draft riggings.

Another and more specific object of the invention is to provide a yoke and draw-bar connecting means employing two blocks arranged to fit the draw-bar shank and engage the shoulders on the butt thereof, said blocks having shoulders or gibs, preferably provided with a pitch, for coöperable engagement with shoulders or gibs formed on the yoke.

The invention furthermore consists in the improvements of the parts and devices and in the novel combinations of the parts and devices, as herein shown, described or claimed.

In the drawing forming a part of this specification, Figure 1 is a side elevation of a yoke and draw-bar showing one form of my improvements. Fig. 2 is a top plan view of the structure shown in Fig. 1. Figs. 3 and 4 are vertical sectional views taken respectively on the lines 3-3 and 4-4 of Fig. 1, and Fig. 5 is a detail perspective view of one of the blocks employed with my construction. Fig. 6 is a part side elevation, part vertical section of another structure embodying my invention. Fig. 7 is a top plan view of the structure shown in Fig. 6. Figs. 8 and 9 are vertical sectional views taken respectively on the lines 8-8 and 9-9 of Fig. 6, and Fig. 10 is a detail perspective view of the block employed in this construction. Fig. 11 is a part side elevation, part vertical section of still another construction embodying my improvement. Fig. 12 is a top plan view of the structure shown in Fig. 11. Figs. 13 and 14 are vertical sectional views taken respectively on the lines 13 and 14 of Fig. 11, and Fig. 15

is a detail perspective view of a block employed in this construction.

In said drawing, and referring to Figs. 1 to 5 inclusive, the draw-bar 10 is shown as provided with the usual upper and lower shoulders 11-11 and coupler key slot 12. The yoke, designated generally by the reference A, is shown as comprising an upper arm 13, lower arm 14 and rear connecting piece 15. At their forward ends, the arms 13 and 14 are flared as indicated at 16 and provided at their extreme ends with T-shaped heads 17-17, said T-heads 17 being provided with a slight pitch, as clearly indicated in Fig. 2 by the dotted lines, to thereby co-act with the blocks, hereinafter described, in the manner of a nut and thread. For attaching the T-heads to the draw-bar, I provide two like blocks 18-18, each of which consists of a side wall 19 fitting against the side of the draw-bar shank, an upper inwardly extending portion 20 engaging half of the top of the draw-bar shank, a lower inwardly extending portion 21 engaging the under side of the draw-bar shank, and a centrally disposed elongated boss 22 adapted to fit the coupler key slot of the draw-bar. Each portion 20 and 21 is provided with a groove or slot 23 of substantially T-shape in cross section, said groove in reality acting as a thread and being pitched to correspond with the pitch of the T-heads 17-17. At their inner ends, each portion 20 and 21 is provided with a shoulder 24 adapted to engage the shoulders 11 of the draw-bar. The blocks 18-18 are fitted over the draw-bar shank with the bosses 22 in the coupler slots and the blocks then secured in position by a rivet 25 or other suitable means and for additional protection, rivets 26-26 may be used as clearly indicated in Figs. 1, 2 and 3. To assemble the yoke with the draw-bar with the blocks in position, the yoke is turned to horizontal position, as indicated by dotted lines in Fig. 4, and is then rotated through an arc of 90 degrees to thereby thread the T-heads 17 into the slots 23-23. On account of the pitch provided in the slots 23 and T-heads 17, the yoke will be pulled toward the draw-bar to its proper position and to retain the same in this position I may provide a pin 27 which extends through suitable perforations in the upper and lower arms of the yoke and through the usual standard rivet 11.

hole in the draw-bar butt, said key or pin being held in position by a cotter or smaller key 28. As will be understood, in draft, the shoulders on the upper and lower sides of the T-heads 17 will engage with the shoulders formed by the enlarged portions of the slots 23-23 and thus pulling strains from the draw-bar are transmitted through the shoulders 11 to the shoulders 24 of the blocks and thus through the latter to the yoke.

In the construction shown in Figs. 6 to 10 inclusive, the yoke B is shown provided with a forward hood or box-like end 30, the same consisting of upper and lower walls 31-31 and side walls 32-32. The draw-bar 110 is provided with the usual upper and lower shoulders 111-111 and coupler key slot 112. The inner end of the draw-bar butt, as shown, is cylindrical in form as indicated at 33 to permit the hooded end of the yoke to be rotated thereabout when the yoke and draw-bar are attached, as hereinafter described. Secured to the draw-bar are two blocks of like construction 118-118, each of which consists of a vertical side wall 119, upper portion 120, lower portion 121 and centrally located boss 122 adapted to fit within the coupler key slot 112. Each portion 120-121 is provided near the inner end thereof with a shoulder 124 arranged to engage the draw-bar shoulders 111. On their outer faces, each portion 120 and 121 is provided with a series of alternate grooves 34 and ribs 35 forming a thread inasmuch as said grooves and ribs or shoulders are pitched as indicated by the dotted lines in Fig. 7. On the inner sides of each of the upper and lower walls 31-31 of the hooded end of the yoke, is provided a corresponding series of alternate ribs or shoulders 36 and grooves 37 pitched to correspond with the pitch of the grooves and ribs 34 and 35. As will be understood, the blocks 118 are fitted over the draw-bar shank and may be secured in place thereon by any suitable means, such as the rivets 125-125. The yoke is attached to the draw-bar by first placing the yoke in the horizontal position as indicated by dotted lines in Fig. 8, after which the yoke is given a quarter turn and the corresponding ribs and grooves interengage as shown more clearly in Fig. 6. As in the construction shown in Figs. 1 to 5 inclusive, upon forward movement of the draw-bar, the shoulders thereon will engage the shoulders 124 of the block and the latter through the shoulders, gibs or ribs formed on the outer face thereof by engagement with the corresponding parts of the yoke will pull the latter forwardly.

In the construction shown in Figs. 11 to 15 inclusive, the yoke C is shown as provided with a hooded forward end 230, the same having outwardly bowed side walls 232

and upper and lower walls 231-231. The draw-bar 210 is provided with the usual coupler key slot 212, upper and lower shoulders 211 and inner butt 233 rounded on its upper and lower faces, as clearly indicated in Fig. 1. For forming the connection between the yoke and the draw-bar I provide a pair of similar blocks 218-218, each of which consists of a side wall 219, upper portion 220 and lower portion 221. The portions 220 and 221 are so formed that their inner faces 224 form shoulders for engagement with the draw-bar shoulders 211 and the outer faces of said portions 220 and 221 are provided with a slight pitch (see Fig. 12) and form shoulders 235-235 for engagement with inwardly turned shoulders or gibs 236 formed on the inner sides of the upper and lower walls 231 of the yoke hood, it being understood that the gibs or shoulders 236 are also pitched to correspond with the pitch on the shoulders 235. Preferably, each block 218 has the side wall thereof extended in the form of an ear 40 perforated to receive a rivet 225 by which the blocks may be rigidly secured to the draw-bar. The yoke is applied in the manner hereinbefore set forth for the other two constructions, that is, by first placing the yoke in horizontal position, as indicated by dotted lines in Fig. 13, and then giving it a quarter turn to bring the shoulders thereon into operative engagement with the shoulders on the blocks.

From the preceding description, it will be seen that in each of the constructions shown and described, each pair of blocks is of like construction; the same may be cheaply manufactured by casting; they may be readily attached to and detached from any standard draw-bar having the usual upper and lower shoulders; and the blocks may be so formed as to adapt them for a wide variety of connections therebetween and the yoke.

Although I have herein shown and described the forms which I now consider preferable for carrying out my invention, I do not wish to be confined to the specific constructions shown and described.

What I claim is:

- In a device of the character described, the combination with a draw-bar having shoulders and provided with a coupler key slot, of a yoke having gibs on the forward ends of the arms thereof, blocks fitting the draw-bar shank and in engagement with said draw-bar shoulders, said blocks being provided with shoulders coöperable with said gibs of the yoke, the engagement of the block shoulders and yoke gibs being effected by a quarter turn relatively between the yoke and draw-bar after the blocks are positioned on the latter, and means extending through said blocks and said draw-bar slot for retaining said blocks in place.

2. In a device of the character described, the combination with a draw-bar having upper and lower shoulders, and a yoke, the forward ends of the arms of which are provided with gibbs, of a pair of blocks fitting over the sides, top and bottom of said draw-bar shank and having meeting faces forming a vertical division therebetween, and means for securing said blocks to the draw-bar, said blocks having upper and lower shoulders coöperable with said gibbs of the yoke and the engagement of said gibbs and shoulders being effected by a relative rotation of the draw-bar with the blocks thereon and said yoke.

3. In a device of the character described, the combination with a draw-bar having shoulders, of a yoke having gibbs at the forward end thereof, and means for connecting

said yoke with the draw-bar, said means comprising a pair of blocks fitting and surrounding the top, bottom and sides of draw-bar shank and engageable with said draw-bar shoulders, said blocks being provided with shoulders coöperable with the gibbs of said yoke, said shoulders and gibbs being provided with a pitch and the engagement being effected by a turn relatively between the yoke and draw-bar after the blocks are positioned on the latter.

In witness that I claim the foregoing I have hereunto subscribed my name this 4th day of March, 1915.

JOHN F. O'CONNOR.
